UNITED STATES PATENT OFFICE.

CARL F. LEMKE, OF CHICAGO, ILLINOIS.

TOY.

1,364,388.

Specification of Letters Patent.

Patented Jan. 4, 1921.

Application filed November 11, 1919. Serial No. 337,150.

To all whom it may concern:

Be it known that I, CARL F. LEMKE, a citizen of the United States, residing at 2712 No. Francisco Ave., city of Chicago, in the 5 county of Cook and State of Illinois, have invented new and useful Improvements in Toys, of which the following is a specification.

This invention relates to toys consisting of 10 one or more movable figures, and its object is to provide a toy having figures which are movable to simulate certain military evolutions or other movements.

The object stated is attained by means of 15 a novel combination and arrangement of parts to be hereinafter described and claimed, and in order that the same may be better understood, reference is had to the accompanying drawing forming a part of this 20 specification.

In the drawing,

Figure 1 is a perspective view of the toy, and

Fig. 2 is a cross section thereof.

Referring specifically to the drawing, the 25 toy is composed of one or more figures 5 carried by a base 6 which is adapted to be dragged back and forth across the floor, a table top, or any other smooth supporting 30 surface.

The base 6 is in the form of a shallow rectangular box having its top and bottom made of card board, and its sides of wood. On the bottom wall of the box are knobs or 35 feet 7 for spacing the same from the surface along which the toy is to be dragged.

Each figure 5 represents a soldier, the same being mounted to turn about a vertical axis so that it may simulate the movement of a 40 soldier going through the evolution of

"right-face," "right-about," etc., according to the initial position of the figure. This movement of the figure is attained by providing the same with a pin 8 depending from its base and passing loosely through 45 the top and the bottom of the base 6 to depend from the latter a sufficient distance to be in contact with the table or other surface along which the toy is to be dragged. The lower depending end of the pin 8 has a lateral bend 9, so that its extremity, which is in 50 sliding contact with the table surface, does not coincide with the pivotal axis of the figure but is off to one side thereof. This arrangement causes the figure to turn when the 55 toy is dragged along the table or other surface, the action being similar to that of a caster wheel.

It will be understood that the toy may be provided with figures other than that of 60 soldiers, and any number of figures may be provided. When a plurality of figures are provided, as illustrated, they move together.

The base 6 is provided with a handle 10, whereby the toy may be manipulated. 65

I claim:

A toy comprising a base having means whereby it may be slidably positioned on and spaced from a supporting surface, a vertical pivot member carried by the base 70 and depending therefrom, the depending portion of the pivot member having its extremity positioned off to one side of the axis of said member and adapted to come into sliding contact with the supporting surface, 75 and a figure carried by the pivot member and positioned above the base.

In testimony whereof I affix my signature.

CARL F. LEMKE.
